UNITED STATES PATENT OFFICE.

ISADORE FRY AND JACOB SHANKS, OF ST. LOUIS, MISSOURI.

PHONOGRAPH ATTACHMENT FOR PLAYER-PIANOS.

1,123,512.

Specification of Letters Patent.

Patented Jan. 5, 1915.

Application filed October 18, 1913. Serial No. 796,081.

To all whom it may concern:

Be it known that we, ISADORE FRY and JACOB SHANKS, a citizen of the United States and a subject of the Czar of Russia, respectively, and residents of St. Louis, Missouri, have invented certain new and useful Improvements in Phonograph Attachments for Player-Pianos, of which the following is a specification containing a full, clear, and exact description, reference being had to the accompanying drawings, forming a part hereof.

Our invention relates to improvements in phonographic attachments for player pianos, and the object of our invention is to 15 operatively combine with the driven mechanism of a player piano a phonograph which may be connected to and disconnected from the player mechanism as desired, and which 20 may be reset to repeat with the rewinding mechanism of the music roll.

With the above purposes in view our invention consists in certain novel features of construction and arrangement of parts as 25 will be hereinafter more fully described, pointed out in the claims and illustrated by the accompanying drawings, in which—

Figure 1 is a front elevation of a player piano, certain parts being removed, showing the relative arrangement of the player mechanism with a phonograph as contemplated by our invention; Fig. 2 is an enlarged detail plan illustrating the detachable gear connections between the driven 35 music roll of the player piano and a phonograph; Fig. 3 is a front elevation of the parts shown in Fig. 2; Fig. 4 is an end view of the parts shown in Figs. 2 and 3; Fig. 5 is a transverse sectional elevation taken on 40 the line 5—5 of Fig. 3; Fig. 6 is a transverse sectional elevation taken on the line 6—6 of Fig. 2; and Fig. 7 is a detail sectional plan illustrating the clutch connection between the player piano mechanism and the phonographic mechanism.

Referring by numerals to the accompanying drawings: 8 designates the piano casting and 9 the sound board thereof, both of which are or may be of any desired construction.

10 designates a cabinet in which is journaled a motor driven shaft 11 carrying a spool 12 and a second shaft 13 carrying a spool 14. Arranged to be wound upon the 45 spools 12 and 14 is the ordinary perforated sheet 15.

Connected with the shaft 11 is the ordinary motor (not shown) and this motor is equipped with the ordinary reversing mechanism (not shown). All player pianos are 60 equipped with such a reversible motor and hence it was not deemed necessary to illustrate it in detail.

16 designates a shaft which is secured in a position conveniently accessible to the operator and is equipped with an ordinary lever 17.

18 designates a shaft arranged parallel with the shaft 16 and which carries at its one end an arm 19 and at its other end an 70 arm 20. Connected with the arm 20 is a link 21 leading to the reversing mechanism of the motor, previously referred to.

Secured to the sound board 9 is a frame 22 and rotatably mounted in said frame is a 75 support 23 for a phonographic record of the cylinder type, and located beneath the cylinder support is a feed shaft 24.

25 designates a pulley which is secured to rotate with the cylinder support 23, and 26 80 designates a pulley mounted on a shaft 27 in the frame 22. Embracing the two pulleys 25 and 26 is a belt 28 forming a direct drive between the shaft 27 and the cylinder support 23.

Secured to the shaft 27 is a pinion 29 having a clutch member 30 carried thereby. The pinion 29 meshes with a gear wheel 31 carried by the shaft 11 which is the motor driven shaft of the piano player mechanism; 90 It will be obvious from this gear connection that when the music rolls are driven the record and support 23 will be driven.

32 designates a clutch member which is feathered to the shaft 27 and 33 designates 95 a lever for the operation of the clutch member 32. By this means the operator may disconnect the phonograph from the piano player, if desired.

In order to secure uniformity of action, 100 we have arranged an ordinary centrifugal governor 34 which is geared to the shaft 27 through the medium of the gear wheels 35. The one end of each leaf carrying the balls of the governor is secured to a sleeve 36, and 105 connected with the sleeve is a bell crank lever 37 which is held in one position by means of a spring 38 and its one end impinges an adjustable set screw 39. Through this medium different tensions may be put 110 on the springs on the governor, thereby controlling its speed as desired.

Supported in the frame 22 and parallel-
ing the feed shaft 24 is a shaft 40 which con-
stitutes a support for the frame 41 carrying
the sound box 42.

- 5 43 designates an arm carried by the frame
41 and arranged to support the feed nut 44
which coacts with the feed shaft 24 to move
the sound box longitudinally of the phono-
graph record 45 carried by the support 23.
10 As shown in Fig. 5, the relative arrange-
ment between the feed nut 44 and the sound
box 42 is such that when the sound box is
elevated to free it from the record, the nut
44 is elevated above the feed shaft.
15 Extending parallel with the feed shaft 24
is a rail 46 and fulcrumed to the frame 41 of
the sound box is a lever 47. Secured to said
lever 47 is a rod 48 connecting with a lever
49 which in turn has secured thereto a link
20 50 connected with the arm which controls
the motor and its reversing mechanism.

Assuming the phonograph to be connected
to play with the piano and the operator de-
sired to repeat both the music and the record
25 of the phonograph, the lever 17 is grasped
and, through the medium of the shafts 16
and 17 and the link 21, the motor is re-
versed. At the same time that the music
sheet is reversed the rod 50, through the
30 medium of the lever 49 and rod 48, the lever
47 is brought to bear against the rail 46,
thereby tilting the sound box frame 41
which frees the reproducing needle and the
feed nut 44, so that a continued movement
35 of the rod 48 will move the entire sound box
and its accompanying parts to the initial
end of the record.

We claim:

1. In a phonographic attachment for
40 player pianos, means for controlling a motor

and a rewinding mechanism for the player
piano; a phonograph; a gear connection be-
tween the phonograph and the player
mechanism; and means including a connec-
tion between the sound box of the phono-
graph and the means for controlling the
motor and the rewinding mechanism where-
by, upon a movement of said controlling
means which will effect a rewinding, the
sound box of the phonograph will be set to 45
its initial position.

2. In combination with a player piano
having means for controlling its motor and
rewinding mechanism; a phonograph hav-
ing a movable sound box; means for con-
necting and disconnecting the phonograph
with the player piano mechanism; and a
connection between said sound box and the
means for controlling the motor and re-
winding mechanism. 50

3. In combination with a player piano,
having means for winding and rewinding
music rolls and a lever for the control of
said winding and rewinding means; a
phonograph having a movable sound box; 65
a gear connection between said phonograph
and its sound box and said winding and re-
winding means; and means including a con-
nection between said sound box and said
lever, whereby a moving of the sound box 70
may be accomplished at the time said wind-
ing and rewinding means is operated.

In testimony whereof, we have signed our
names to this specification, in presence of
two subscribing witnesses.

ISADORE FRY.
JACOB SHANKS.
